Application July 30, 1953, Serial No. 26,185

Term of patent 14 years

(Cl. D44—15)

To all whom it may concern:

Be it known that I, Martin Rosen, a citizen of the United States and a resident of the city of New York, county of Queens, and State of New York, have invented a new, original, and ornamental Design for a Vegetable Dish, of which the following is a specification, reference being had to the accompanying drawings, forming a part hereof.

Fig. 1 is a top plan view of a vegetable dish showing my new design;

Fig. 2 is a bottom plan view thereof;

Fig. 3 is a side elevational view thereof; and

Fig. 4 is an end elevational view thereof.

I claim:

The ornamental design for a vegetable dish, as shown.
